CLAIM

I claim, the ornamental design for a wheel balance weight, as shown and described.

DESCRIPTION

FIG. 1 is a perspective view of a wheel balance weight showing my new design;

FIG. 2 is a front elevational view thereof,

FIG. 3 is a rear elevational view thereof,

FIG. 4 is a left side elevational view thereof,

FIG. 5 is a right side elevational view thereof,

FIG. 6 is a top plan view thereof;

FIG. 7 is a bottom plan view thereof.

FIG. 8 is an enlarged top view thereof taken from part A in FIG. 6; and,

FIG. 9 is an enlarged cross sectional view thereof taken along the line B-B in FIG. 8.
